UNITED STATES PATENT OFFICE.

JOSEPH WHARFE, OF LONDON, ENGLAND.

HOOK FOR TOASTING, &c.

SPECIFICATION forming part of Letters Patent No. 543,916, dated August 6, 1895.

Application filed March 18, 1895. Serial No. 542,279. (No model.)

To all whom it may concern:

Be it known that I, JOSEPH WHARFE, a subject of the Queen of Great Britain, and a resident of Wimbledon, London, in the county of Surrey, England, have invented certain new and useful Improvements in Hooks for Toasting or the Like, of which the following is a full, clear, and exact specification thereof.

This invention relates to a hook for use when toasting and like purposes, and the same is carried out as follows, reference being had to the annexed drawings, in which—

Figure 1 is a perspective view of my hook. Fig. 2 shows the blank from which same is formed, and Fig. 3 a perspective view showing hooks in position for toasting.

a is a piece of metal, such as sheet iron or steel, in which the tongue or arm d is cut or stamped out and bent up, as shown, having notches c in same, one end of the piece a being bent so as to form a hook b.

The hooks are hung upon the bar f of a grate, Fig. 3, and a rod or skewer g, carrying the article to be toasted or cooked, is placed

upon the arm d, the distance from the fire being regulated by the notches c. It will be seen that the distance between the hooks can be varied to suit the width of the grate upon which they are used.

The dotted lines marked e represent the position of the cut-out or stamped tongue or arm.

Having thus described my invention, what I claim is—

A hook for toasting formed from a blank; a tongue or arm cut out and bent up; notches upon said arm; a turned over or bent end upon said blank, in combination with a rod or skewer engaging on said arm substantially as described.

In testimony that I claim the foregoing I have hereunto set my hand this 25th day of January, 1895.

JOSEPH WHARFE.
